FIG. 1 is a perspective illustration, from the front and left side, of a seating and tire arrangement of an all terrain vehicle according to our design;

FIG. 2 is a perspective illustration, from the rear and left side, of the seating and tire arrangement illustrated in FIG. 1;

FIG. 3 is a left side elevational view of the seating and tire arrangement of FIG. 1;

FIG. 4 is a right side elevational view of the seating and tire arrangement of FIG. 1; and,

FIG. 5 is a top plan view of the seating and tire arrangement of FIG. 1.

In FIGS. 1–5, broken lines showing environment or structure are for illustrative purposes only and form no part of the claimed design.
